UNITED STATES PATENT OFFICE.

SULLIVAN PALMERI, OF PLANTSVILLE, CONNECTICUT.

SPARK PLUG.

Application filed March 16, 1923. Serial No. 625,441.

To all whom it may concern:

Be it known that I, SULLIVAN PALMERI, a citizen of the United States, residing at Plantsville, in the county of Hartford and State of Connecticut, have invented a new and useful Improvement in Spark Plugs; and I do hereby declare the following, when taken in connection with the accompanying drawings and the characters of reference marked thereon, to be a full, clear, and exact description of the same, and which said drawings constitute part of this application, and represent, in—

Fig. 1 a side view, partly in section, of a spark plug constructed in accordance with my invention.

Fig. 2 a side view of the housing-cap detached.

This invention relates to improvement in spark plugs, and particularly to plugs provided at their lower ends with chambers within which the contact portions of the electrodes are housed, the object of this invention being a simple arrangement of parts, whereby a cap may be readily fitted over the inner end of a spark plug and provides the desired housing, and the invention consists in the construction as hereinafter desired and particularly recited in the claim.

In illustrating my invention, I have shown it applied to a conventional form of spark plug, including a casing 5, provided at its

lower end with a transverse, fixed electrode 6, which is in the form of a pin, the ends of which project beyond the outer side walls of the lower end of the casing, so as to enter bayonet-slots 7 opening out of the upper end of a cap 8, which is provided, near its lower end, on opposite sides, with slots 9. The fixed electrode 6 thus forms a support for the housing-cap, so that the cap may be readily applied or removed when desired,—something which is difficult to do if the cap has a screw connection with the plug, as more or less corrosion takes place. 45

I claim:

A spark plug provided with a transverse pin-like electrode permanently mounted in the inner end of the plug and longer than the diameter of the plug, so as to project beyond opposite sides thereof, a housing-cap formed with bayonet slots engaging with the projecting ends of the said electrodes, whereby the cap is locked in place by said electrode, the said cap also formed on one side 55 with a slot.

In testimony whereof, I have signed this specification in the presence of two subscribing witnesses.

SULLIVAN PALMERI.

Witnesses:

RALPH MONTE,
THOMAS F. WELCH.
